UNITED STATES PATENT OFFICE.

GEORGE T. BROWN, OF JACKSON, MICHIGAN.

DESIGN FOR A SUPPORT FOR HOSE-NOZZLES.

SPECIFICATION forming part of Design No. 26,940, dated April 20, 1897.

Application filed February 11, 1897. Serial No. 623,015. Term of patent 14 years.

To all whom it may concern:

Be it known that I, GEORGE T. BROWN, a citizen of the United States, residing at Jackson, in the county of Jackson and State of Michigan, have invented and produced a new and original Design for a Support for Hose-Nozzles, of which the following is a specification, reference being had to the accompanying drawing, forming a part thereof.

10 The accompanying drawing shows in perspective a hose-nozzle support embodying my design.

The leading features of my design consist in the somewhat removed and oppositely-extended curves or rests conformed to the shape of the forward upper side and rear under side, respectively, of a hose-nozzle.

15 The rear under rest a is downwardly curved at the upper end of a fork or prop a' , and the

forward rest b is carried forward by arms b' , 20 having a shape to lie substantially straight alongside of the nozzle, the rest b extending upwardly at b^2 and having a form to fit the contour of the forward end of the nozzle and having loops b^3 and angular portions b^4 , a bar 25 c extending across the latter from one side of the fork to the other.

I claim—

The design for a support for a hose-nozzle, substantially as shown and described. 30

In testimony whereof I have signed my name to this specification in the presence of two subscribing witnesses.

GEORGE T. BROWN.
